United States Patent Office.

FREDERICK S. FAHNESTOCK, OF CHICAGO, ILLINOIS.

Design No. 4,616, dated January 31, 1871.

DESIGN FOR A SEWING-MACHINE SAMPLE-TRUNK.

The Schedule referred to in these Letters Patent and making part of the same.

To all whom it may concern:

Be it known that I, FREDERICK S. FAHNESTOCK, of Chicago, in the county of Cook and State of Illinois, have invented and produced a new and original Design for a Sewing-Machine Sample-Trunk, of which the following is a specification, reference being had to the accompanying drawing.

My invention relates to sample-trunks or boxes, and consists in constructing them in a novel manner as to the arrangement of the interior, so that a sewing-machine, or the working parts of one, may be securely packed therein for the purpose of transportation, and, when the box is open, permit of the machine being operated or exhibited without requiring to be removed therefrom.

In the accompanying drawing—

Figure 1 is a perspective view of the trunk or box when closed.

Figure 2 is a perspective view, showing the trunk open.

A A' represents the two halves of a trunk or case, hinged together in the usual way, and provided with lock, straps, and handles, as desired.

B is a partition or board, fitted and secured in the

half A', and projecting therefrom, its outer end being shaped so as to fit easily into the half A when the trunk is closed.

To this board B the main working parts of the sewing-machine are attached in the same manner as they are attached ordinarily to the tops or tables of sewing-machine frames.

It will be seen that when the trunk is open and standing on end, as shown by fig. 2, the sewing-machine secured therein may be operated with facility in the usual manner. And when the trunk is closed, as shown by fig. 1, it is packed and ready for transportation, without additional preparation or further trouble than that of locking and securing the straps.

The trunk thus constructed and arranged is of great convenience and utility to traveling agents and others engaged in the sale of sewing-machines.

I claim as my invention—

The design for a sewing-machine sample-trunk, as herein shown and described.

FREDERICK S. FAHNESTOCK.
